UNITED STATES PATENT OFFICE.

EDWARD Y. MOORE, OF CLEVELAND, OHIO.

HELICOPTER.

Application filed March 28, 1923. Serial No. 628,206.

To all whom it may concern:

Be it known that I, EDWARD Y. MOORE, a citizen of the United States, residing at Cleveland, in the county of Cuyahoga and State of Ohio, have invented a certain new and useful Improvement in a Helicopter, of which the following is a full, clear, and exact description, reference being had to the accompanying drawings.

10 This invention relates to improvements in helicopters such as are shown in my application Serial No. 623,815, filed March 7, 1923.

Briefly, the helicopter shown in my prior application embodies a plurality of helicopter propellers so mounted, that the angle of the axis of each propeller shaft may be varied relatively to the frame, wherefore the forward motion of the ship may be obtained without additional propellers. The mechanism shown is arranged to move all of the propeller shafts simultaneously through varying degrees for controlling the rise and descent, as well as the forward travel including stopping, starting and hovering.

25 An object of the present invention is to arrange mechanism for controlling the propellers so as to obtain independent angular movement and thus to employ the propellers for steering the ship, and for balancing and 30 stabilizing it, as well as to provide an effective brake upon the forwardly moving ship.

Another object of the present invention is to the arrangement of power mechanism under manual control for effecting the swinging of the propellers.

35 In accomplishing the above objects, I prefer to employ two pairs of propellers, all of which are arranged to be driven from the same source of power. The rear propellers are arranged to be swung in unison, while the front propellers may be swung independently of the rear propellers and independently of each other. An advantage of this arrangement is that the ship may be readily steered while in forward motion, may be readily stabilized even in a high wind, and may be balanced if unevenly loaded.

40 A simple embodiment of my invention is shown somewhat diagrammatically in the accompanying drawings to which the following description relates.

45 In the drawings, Fig. 1 is a plan view showing a plurality of propellers carried by the frame and illustrating the driving and controlling means; Fig. 2 is a side elevation of the same showing the angle of the forward

propellers shifted away from the vertical; Fig. 3 is an illustrative embodiment of a ship consisting of fuselage gliding wings and rudder which may be grouped about 60 such helicopter frame; Fig. 4 is a plan view of a complete airship.

In the drawings, I have shown four propellers arranged in pairs and designated 10—10, 12—12 respectively, each of which may consist of two or more blades and may be designed for the particular weight and speed of the ship.

These propellers are shown as mounted upon upwardly extending bracket arms 14 and 15 respectively, each of which may be rigid with a transversely extending tubular member through which the driving connection for the propeller may extend. The hollow members adjacent the forward propellers are indicated at 16 and 17 as being supported on bearings 18 and 19, respectively, which may comprise part of the frame. The transverse hollow member adjacent the rear propellers, indicated at 20, is provided intermediate with a bridge member 21 as shown particularly in Fig. 1. The member 20 may be supported at 22 in bearings which may also comprise part of the frame.

To drive the propellers, I have shown a suitable source of power as a motor 25, which for convenience is illustrated as being supported on longitudinal members 26 of the frame. The connection between the motor and the propellers may be any convenient arrangement, but I have illustrated the motor as being disposed intermediate the forward and rear propellers, and as having drive shaft extensions 27 and 28 extending forwardly and rearwardly thereof, to drive 95 the respective forward and rearward propellers.

To transmit power from the shaft 27 to the forward propellers, I have illustrated a bevel gear 30 which meshes with companion gears 31 and 32 on the transverse shafts 33 and 34 respectively. These shafts are supported in the tubular members 16 and 17 and may be provided at the outer ends with bevel gears 35 and 36 which mesh with companion gears 37 and 38, on the propeller shafts 39 and 40 respectively.

The mechanism for operating the rear set of propellers is indicated as comprising a bevel gear 41 which drives companion gears 42 and 43 on shafts 44 and 45 respectively. These shafts may be provided with

bevel gears 46 and 47 which mesh with companion gears on the rear propeller shafts 50. The arrangement of the mechanism shown may be materially altered to suit the design of any helicopter, and is used to illustrate the frame and driving means for two or more propellers; it being understood that the driving means is arranged to permit the rocking of the propellers as described.

To accomplish the change in the angle of the rear propeller shafts, I provide mechanism for shifting the rear propellers simultaneously, but independently of the front propellers and I provide mechanism for shifting each front propeller independently of the other.

A simple means for shifting the rear propellers is indicated by a worm wheel 55 rigid with the tubular member 20 and a cooperating worm 56 which may be carried by a shaft 57. The shaft may be controlled by selective gears 58 which are adapted to be controlled by a shift lever 59. The driving gears 58 may be constantly rotated by a shaft 60 which in turn is shown as being rotated by the worm and worm wheel connection 61 from the drive shaft 27. An extension rod 62 may be connected to the shift lever 59 for enabling the gears to be controlled from the driver's seat. With this arrangement, the lever 59 may be shifted to bring either of the opposed gears 58 into engagement with the companion gear on the shaft 57, wherefore the direction in which the shaft 57 is rotated may be controlled at will.

To obtain independent angular movement of the forward propeller shafts, I have illustrated a convenient mechanism as embodying selective gears 65 and 66 respectively which may be rotated by companion gears on the constantly rotating shaft 60. Suitable shift levers 67 and 68 may be operatively connected to extension rods 69 and 70, respectively, for controlling the gears 65 and 66, and hence for controlling the direction of rotation of the shafts 71 and 72 respectively. These shafts may be directly connected to the tubular members 16 and 17 by worm and worm wheel connections 73 and 74 respectively. With this arrangement the shafts 71 and 72 may be rotated independently of each other and also independently of the shaft 57, wherefore the forward propellers may be moved in unison with the rear propellers or may be moved independently of the rear propellers. Similarly the front propellers may be moved independently of each other and independently of the rear propellers wherefore the action of the propellers may serve as an effective brake upon a moving ship.

In Figs. 3 and 4 I have shown the fuselage 80 as carrying suitable side wings 81,

a rudder 82 and tail wings 83 which may be employed for gliding or, if desired, for additional maneuvering control.

From the foregoing description, it will be seen that I have provided a mechanism which enables sets of helicopter propellers to be positioned as a unit or independently without interfering with the rotation of the propellers; wherefore, I may obtain an arrangement which enables a ship to rise vertically, to effect hovering and obtain forward travel, and at the same time to be steered as desired. Moreover, this arrangement enables the ship to be easily controlled even in a high wind, to be brought into proper balance if the load therein is not uniformly distributed on all the propellers, and to be effectively stopped when traveling in a forward direction. As explained, the shifting of the propellers may be effected by mechanical power under simple manual control.

Having thus described my invention, I claim:

1. In a helicopter, the combination of a frame, of four propellers, a motor geared with all of said propellers for rotating them, mechanism for varying the position of the axis of rotation of two of the propellers as a unit, two mechanisms for respectively varying the axis of rotation of the other propellers, and three controls for said three mechanisms.

2. In a helicopter, the combination of a frame, a motor mounted thereon, two pairs of propellers, driving mechanism between the motor and each propeller, mechanism for changing the angle of the axis of rotation of both propellers of one pair simultaneously, two mechanisms for changing the angle of the axis of rotation of the other two propellers independently, and means for coupling each of the three mechanisms mentioned with the motor.

3. In a helicopter, the combination with a frame, of two pairs of propellers, a motor on the frame for driving the propellers, selective power operated mechanism for enabling the axes of rotation of all the propellers to be simultaneously changed, said mechanism being also arranged to permit a change in the angle of the axis of rotation of two of the propellers independently of each other and of the other two.

4. In a helicopter, the combination with a frame, of two pairs of propellers carried thereby, a motor on the frame for driving the propellers, and selective mechanism operable by the motor for enabling the angle of the axis of rotation of all the propellers to be changed simultaneously, and for enabling the angle of one propeller to be changed independently of the angle of the other propeller in the same pair, independently of the others.

5. In a helicopter, the combination with a frame, of a motor, four propellers adapted to be driven thereby, mechanism for independently varying the angles of the axes of rotation of two propellers with relation to the frame, with relation to the other propellers, and with relation to each other, and manually operable means for connecting said mechanism with said motor.
- 10 6. In a helicopter, the combination of a frame, a motor mounted on the frame and having a fore and aft shaft, two lateral shafts bevel geared with said fore and aft shaft, two substantially upright shafts bevel geared with the lateral shafts, propellers
- on the upright shafts, whereby the motor may operate said propellers simultaneously, and mechanism for swinging each of said upright shafts independently of the other upright shaft, the last mentioned mechanism including rotatable sleeves around the lateral shafts carrying the upright shafts, mechanisms for turning said sleeves, and two independently controlled mechanisms for coupling the turning mechanisms with the motor.
- 15 In testimony whereof, I hereunto affix my signature.

EDWARD Y. MOORE.
